LUBRICATING OIL SUPPLY SYSTEM

Carl B. Sues, Lancaster, Calif.

Application December 20, 1946, Serial No. 717,367

7 Claims. (Cl. 184—103)

1

The present invention relates to lubricating oil supply systems for use with internal combustion engines, and the primary object of the invention is to provide a device for automatically replenishing the lubricating oil supply of any high speed internal combustion stationary or marine engine as the oil is used up during its operation, with oil drawn from a bulk storage container such as a tank or drum. The device thus provides a constant oil level at all times without requiring the attention of an operator except for periodical oil changes and refilling of the tank or replacement of empty drums with full ones. The principal advantage of the invention resulting from the elimination of the need for constant attendance by an operator is that it permits fully automatic operation of engines which have heretofore required attention only for replenishment of the oil. Thus, isolated installations such as aerial beacons or radio weather stations may be left unattended for long periods of time, or in the case of fishing boat engines, electrical generating plants, farm power plants, or the like, the engine can be operated without attention and with absolute assurance that the oil in the engine sump will be maintained at the desired level at all times.

Another advantage of the invention is that the lubricating oil is handled only once, and therefore dirt and other contaminants which are unavoidably introduced each time that the oil is poured from a drum into a container and then into the engine crankcase, is prevented from entering the engine. During the course of using the average drum, the oil is handled approximately seventy-five to one hundred times, and as a result a considerable amount of dirt enters the engine regardless of the care of the operator or cleanliness of conditions. With the present invention the oil is handled only once, and when the storage tank has been refilled or an empty drum disconnected and replaced by a full one, the oil is thereafter sealed off in the system and completely protected from contamination.

Still another advantage of the invention resides in the fact that inasmuch as new oil is added continuously to the engine to replace that which has been used up, it is practical to fill the oil sump to a lower level than would otherwise be necessary since the sump is not required to hold a reserve supply of oil which can be used up before the level drops too low. As a result, a smaller volume of oil is discarded each time the crankcase is drained, with an appreciable saving in oil.

2

Another object of the invention is to provide a device enabling the crankcase to be refilled rapidly after draining by merely opening a valve and permitting oil to flow in relatively large volume directly from the storage container to the crankcase, with appreciable reduction in the shutdown time of the engine for oil changes.

Still another object of the invention is to provide an automatic lubricating oil supply system which can be connected to any drum or tank for gravity feed.

A further object of the invention is to provide a float-controlled oil supply system adapted for use in marine installations and embodying means to prevent surging of oil from the crankcase of the engine to the float chamber of the valve with adverse effect upon the operation of the system.

Essentially, the present invention comprises a valve arrangement interposed between an oil storage tank and the oil sump of the engine and consisting of a normally closed, manually controlled refill valve and an auxiliary float-controlled needle valve which is operable to admit oil from the tank to the sump at the same rate that the oil is used up by the engine. The device is mounted on or closely adjacent to the engine and is provided with a float chamber which communicates with the engine oil sump and which is arranged so that the level in the chamber is the same as the level in the sump. When the oil in the sump and float chamber is at normal level, the float holds the needle valve closed, but as the level drops due to consumption of the oil, lowering of the float causes the needle valve to open, admitting fresh oil to restore the level in both the chamber and sump to normal. When the oil sump is to be refilled after draining, the refill valve is opened manually to permit oil to flow in relatively large volume from the storage tank to the sump until the level is raised to approximately one-half to three-quarters full. The refill valve is then closed, and the float-controlled needle valve thereafter functions automatically to bring the level exactly to the desired point. A second float within the chamber is provided with an indicator stick which can be viewed through an inspection window to check the oil level.

For marine installations where the system is subject to the rolling and pitching of a boat, producing a difference in head between the sump and float chamber, a surge compensator is provided which forms a restriction preventing voluminous flow between the two when the system is on automatic operation with the float-controlled needle

valve replenishing the oil as it is used up. In its preferred form, the surge compensator comprises a pair of elements associated with the outlet line leading from the float chamber to the crankcase which function as check valves to prevent voluminous flow in either direction when the device is on automatic operation. One of these elements consists of a washer seating on the outlet opening and forming a restriction which is ineffective on the relatively small volume flow admitted through the needle valve, but which prevents voluminous flow from the float chamber to the crankcase. When the refill valve is opened, the float chamber becomes flooded and the washer is lifted by a float from its seat to permit the oil to drain rapidly into the crankcase. The other element comprises a butterfly valve which permits oil to flow without restraint from the float chamber to the crankcase, but which closes automatically when oil tends to surge back from the crankcase to the float chamber.

The foregoing and other objects and advantages of the invention will become apparent to those skilled in the art upon consideration of the following detailed description of the preferred embodiment thereof, reference being had to the drawings, in which:

Figure 1 is a schematic view of an installation embodying the principles of the invention;

Figure 2 is an enlarged sectional view taken through the valve housing, showing the device in automatic operation to replenish the oil in the sump as used up by the engine;

Figure 3 is another view of the same, showing the refill valve open to admit oil in large volume to the float chamber and thence to the oil sump for refilling the latter after draining; and

Figure 4 is a top plan view of the valve.

Figure 1 of the drawings shows a typical installation comprising an internal combustion engine 8, elevated oil storage container 9, and valve mechanism, designated generally by the reference numeral 10. The engine 8 may be any type of high speed internal combustion engine, either Diesel or gasoline, and comprises a cylinder block 11, and crankcase 12 made up of top and bottom halves 13 and 14, respectively, having abutting flanges 15 which are connected by bolts 16. The bottom half, or pan, 14 of the crankcase serves as an oil sump for the engine, and the level of the oil contained therein is designated by the broken line L. Projecting from one side of the top half 13 of the crankcase is the usual breather tube 17 which vents the crankcase to the atmosphere and permits escape of combustion gases blowing past the piston rings. While the engine of the illustrative embodiment is shown with the oil sump in the crankcase and the valve 10 mounted directly on the engine, the invention is also applicable to dry sump engines wherein the oil is contained in a separate tank and is circulated through the lubricating system of the engine and returned to the tank by pumps, in which case the valve 10 would be mounted on or adjacent to the oil tank.

The storage container 9 may be either a permanent tank of any desired capacity, or the standard fifty gallon drum in which bulk oil is usually shipped may be used and mounted on a suitable platform. Connected into the bottom end of the tank 9 is an oil pipe line 20 which is connected at its other end to the valve 10, while a second line 21 connects the float chamber of the valve to the drain cock 18 or any other suitable point on the crankcase 13 below the level of the oil in the

4
sump. Both of the lines 20 and 21 are preferably of flexible hose, at least in part, to permit certain height adjustments of the valve housing which will be described later.

5 The valve mechanism 10 comprises a generally cylindrical housing 22 arranged with its axis vertical and having a central cavity 23 which serves as a float chamber. Projecting downwardly from the center of the housing 22 is a boss 24 having an internally threaded aperture 25 communicating with the float chamber 23 which is adapted to receive a coupling 26 connecting the line 21 to the float chamber. A cover plate 27 is secured by fillister head screws 28 to the top of the housing to close the top end of the float chamber 23, and is sealed by a gasket 30.

Formed integrally with the housing 22 along one side thereof is a body portion 31 having a vertically disposed bore 32 extending through to its bottom end. The lower end portion of the bore 32 is tapped to provide a tapered pipe thread 33' which receives a coupling member 34' connecting the supply line 20 to the housing. Preferably, although not necessarily, the coupling member 34 has a cylindrical filter screen 35' at its top end projecting upwardly into the bore 32, for the purpose of filtering out any entrained foreign matter which might obstruct or interfere with the operation of the valves in the housing.

30 The top end of the bore 32 opens into a horizontally disposed cylindrical valve compartment 33, one end of which opens into the float chamber 23 and the other end of which extends through the side of the body 31. The chamber end of 35 the compartment 33 is shouldered at 34 to provide a seat for a radial flange 35 formed on one end of a tubular valve seat sleeve 36. The sleeve 36 is inserted into the end of the compartment with the flange 35 abutting on the shoulder 34, 40 and is held in place by a pin 40 which is passed through aligned holes in the top end of the housing 22 and in the sleeve.

The outer end of the compartment 33 is threaded at 41 to receive a screw-threaded enlargement 42 formed on a tubular extension 43 projecting inwardly from the end of a bonnet 44. The bonnet 44 has a hole 45 extending through its center provided with a threaded construction 46 adjacent its outer end which receives the lead screw threads 50 on the stem 51 of a valve 52, hereinafter referred to as the refill valve since its function is to admit oil in relatively large volume to the crankcase of the engine to refill the same after draining. A hand wheel 53 is screwed onto a threaded stud 54 projecting from the outer end of the valve stem 51 and is secured by a screw 55 which is threaded into a hole in the end of the stud.

55 The head 56 of the valve 52 is adapted to close on the outer end of the valve seat sleeve 36 to seal the compartment 33 from the float chamber 23. A shoulder 60 formed on the back side of the head 56 provides footing for a seal compression spring 61 which bears at its other end on a washer 62. The washer 62 is positioned in the bottom end of a cavity 63 in the tubular extension 43, and is backed up by an O ring seal 64 of oil resistant synthetic rubber. A second washer 65 backs up the O ring seal, and the latter is thus sandwiched between washers and compressed by the spring 61, so that it is expanded against both the stem 51 and wall of the cavity 63 to seal the bonnet against leakage past the stem.

75 The valve 52 is drilled centrally to form an

axially extending passageway 66 which is shoudered at 70 to provide a seat for a needle valve 71. The passageway 66 is intersected by a lateral hole 72 extending through the side of the stem 51 and communicating with the compartment 33. The needle valve 71 is slidably disposed within the passageway 66 and is operable to admit oil in relatively small volume when the refill valve 52 is closed to replenish the oil in the crankcase 12 as it is used up by the engine. A 10 spring 73 in the bottom of the passageway 66 urges the valve 71 away from its seat 70, and the valve is limited in its outward movement by a stop pin 74 which is inserted into a hole in the end of the valve head 56. The head of the stop pin 74 overhangs the end of the passageway 66 and is engageable by a shoulder 75 on the needle valve 71.

A round-nosed pin 76 projects from the inner end of the needle valve 71 in the direction of the float chamber 23 and is engageable by an arm 80 extending upwardly from a bracket 81 which is secured by bolts 82 to the top of a float 83. The float 83 is preferably annular in shape and may be made of any light weight, oil resistant material such as cork or the like. A bushing 84 is fixed to the bracket 81 at the junction of the arm 80 therewith, and a transversely extending fulcrum pin 85 is passed through the bushing and fixedly held in the side walls of the sleeve 36. The fulcrum pin 85 serves as a pivot for the float 83, allowing the latter to swing up and down in an arcuate path as the level of the oil in the float chamber rises and falls.

When the oil level in the float chamber 23 is at the normal height shown in Figure 2 of the drawings and the refill valve 52 is closed on the end of the sleeve 35, the needle valve 51 is held by the float 83 against its seat 70. As the level drops due to consumption of the oil in the crankcase 12, the float 83 swings downwardly about the pivot 85, causing the arm 80 to rock in a counter-clockwise direction away from the pin 76 of the needle valve. Movement of the arm 80 away from the pin 76 allows the spring 73 to push the needle valve 71 off its seat, admitting oil from the compartment 33, through the passages 72 and 66, to the float chamber 23 and thence through the line 21 to the crankcase. As the level in the crankcase and float chamber is raised by the added oil, the float 83 rises with it, closing the needle valve on its seat.

An indicator stick 90 is provided to permit visual check of the oil level in the float chamber which is, of course, indicative of the oil level in the crankcase, and in the embodiment illustrated the stick is disposed vertically in the center of the float chamber 23 and extends upwardly through a hole 91 in the cover plate 27. The hole 91 is slightly larger in diameter than the rod 90, leaving a certain amount of clearance between them. The cover plate 27 has a central, downwardly extending boss 92 on its bottom surface concentric with the hole 91 and an upwardly extending boss 93 on its top surface coaxial with the boss 92. The top boss 93 is counterbored at 94 and threaded at 95 to receive a coupling member 96 for connecting a vent line 97 thereto. The vent line 97 is preferably of flexible hose, and is connected at its other end by a fitting 98 to the breather tube 17, as shown in Figure 1, or to any other suitable point on the top half 13 of the crankcase, and its purpose is to obtain the same pressure conditions in the float chamber 23 as exist in the crankcase. If some such provision for venting the float chamber to the crankcase

were not provided, any slight increase in pressure in the crankcase due to leakage of combustion gases past the piston rings would cause the oil in the crankcase to flow back through the line 21 to the float chamber 23, resulting in an abnormally high level in the float chamber which would cause the float 83 to hold the needle valve 71 closed, even though the level in the crankcase might be dangerously low. The importance of this feature becomes evident when it is realized that a pressure of only two or three inches of water, which is commonly obtained in engine crankcases, even though equipped with a breather tube, will produce a head difference of two or three inches between the respective levels, which would make the device relatively inoperative.

The upper end of the indicator stick 90 is provided with a stripe of green paint 100, with red portions 101 and 102 above and below the green portion. These colored portions of the stick are viewed through an inspection window comprising a hole 104 drilled transversely through the top boss 93. A cylindrical glass tube 105 is disposed within the counterbore 94 and rests at its bottom end on a gasket 106 which is seated on the shoulder formed at the junction of hole 91 with the counterbore 94. The top end of the glass tube 105 is likewise engaged by a gasket 107 surrounded by a washer 108 which is engaged by the bottom end of the threaded tubular extension 110 of the coupling member 96. The glass tube 105 is thus sandwiched between sealing gaskets and is clamped tightly by the coupling 96 to seal the same against leakage of oil past its ends. A cylindrical float 111 is fixed to the stick 90 intermediate its ends and is positioned so that when the oil level in the float chamber 23 is normal, the green portion 100 of the indicator stick is aligned with the inspection hole 104 and can be seen through the latter. If the level in the float chamber 23 drops, the top red portion 101 becomes visible through the inspection hole 104, warning the operator that the level in the float chamber and crankcase is low and that steps should be taken to rectify the situation by refilling the storage tank 9 or checking the valve mechanism 10 for faulty operation. If the level in the float chamber rises above normal, the lower red portion 102 on the indicator stick becomes visible through the hole 104, warning the operator of an abnormal condition which should be investigated.

Where the valve mechanism 10 is to be used with a stationary engine, the stick 90 is terminated at the bottom of the float 111. For marine installations, however, where the engine and oil supply system are mounted in a boat subject to pitching and rolling, producing appreciable momentary differences in head level between the 60 crankcase oil sump and float chamber, a surge compensator is provided which is illustrated in the drawings and designated generally by the reference numeral 112. The surge compensator 112 comprises a washer 113 which is adapted to 65 seat on the top end of the coupling 26 (Figure 2) and functions to prevent the voluminous flow of oil from the float chamber 23 to the engine crankcase, and a butterfly valve 117 disposed within the coupling 26 which operates to prevent 70 surging from the crankcase back into the float chamber. The washer 113 is provided with a central aperture 114 through which is passed an extension 115 of the stick 90. The aperture 114 is slightly larger in diameter than the stick extension 115, leaving a clearance between them of

substantially the same area as the clearances between the needle valve 71 and passage 66. Thus, the relatively small volume of flow admitted by the needle valve is unaffected by the restriction of the washer 113, whereas any tendency for the oil to flow in large volume from the float chamber to the crankcase is effectively prevented.

The bottom end of the stick extension 115 projects below the washer 113 and has a cross pin 116 inserted through a hole therein which is engageable with the bottom of the washer to lift the same off its seat when the float 111 rises above a predetermined level due to flooding of the float chamber by the refill valve. With the washer 113 thus lifted off its seat, the oil in the float chamber is permitted to drain rapidly into the crankcase. Sufficient clearance is provided between the pin 116 and washer 113 when the oil level in the float chamber is normal to permit the level to fluctuate slightly during normal operation without lifting the washer off its seat.

The butterfly valve 117 is freely pivoted on a pin 118 which is inserted through holes in the sides of the threaded nipple of the coupling 26. The pivot pin 118 is offset slightly to one side of center, and the butterfly is movable between the inclined closed position shown in Figure 2 and the vertical open position shown in Figure 3. The butterfly is weighted so as to assume the closed position, but is adapted to be swung to open position by the pressure of oil flowing in large volume from the float chamber to the crankcase, as when the refill valve has been opened. Sufficient clearance is provided around the edge of the butterfly when closed to permit the small volume of oil admitted by the needle valve to pass through without restraint, but any tendency for the oil to surge back up into the float chamber is effectively resisted.

From the foregoing discussion, it will be evident that successful operation of the device depends upon a common oil level in the crankcase and float chamber, and to this end means are provided for adjustably securing the valve mechanism to the engine structure, permitting vertical adjustment of the valve mechanism to accommodate the normal operating level of the oil in the engine crankcase. Such attaching means is preferably in the form of a bracket 120 having a horizontally disposed, elongated flange 121 which is adapted to be mounted against the underside of the bottom crankcase flange 15. Two of the crankcase bolts 16 are used to secure the bracket to the crankcase, said bolts being passed through elongated slots 122 in the flange 121. The purpose of the slots 122 is to accommodate variations in the spacing of the crankcase bolts 16. If the original crankcase bolts 16 are too short to accommodate the added thickness of the bracket flange 121, they may be replaced by slightly longer bolts. Spaced laterally from the flange 121 is a vertically disposed body portion 123 having a vertical channel 124 in its outer face. One side of the channel 124 has a V-notch 125 cut into it which receives a correspondingly shaped portion 126 of a vertically disposed rail 130 formed integrally with the housing 22 and connected therewith by a web 131. Two vertically spaced set screws 132 are screw-threaded into holes in the side of the body 23 opposite the V-notch 125 and engage the flat back side of the rail 130 to clamp the latter tightly into the V-notch 125. Vertical adjustment of the valve mechanism 10 is obtained by merely loosening the set screws 132 and raising or lowering the valve

mechanism to the desired level. At the time the valve mechanism is installed on the engine, the crankcase 12 is first filled to normal operating level and the mechanism is then adjusted up or down until the green mark 100 on the indicator stick becomes visible through the inspection window 104. The set screws 132 are then tightened up.

A shut-off valve 133 is also provided in the supply line 20 just below its point of connection with the storage tank 9, and the purpose of this valve is to permit the flow of oil to be cut off entirely while the engine crankcase is being drained. Except for drain periods, the valve 133 is left fully open at all times.

The operation of the invention is believed to be self-evident from the foregoing description but for convenience will be summarized again. When the oil in the crankcase is to be drained, the shut-off valve 133 is closed and the drain cock 18 is opened. Upon completion of the draining operation, the drain cock 18 is closed and valve 133 is opened. The refill valve 52 is then opened fully by turning the hand wheel 53, and oil is admitted in relatively large volume to the float chamber 23. Because of the restriction in the surge compensator 112, the float chamber 23 becomes flooded, causing the two floats 111 and 83 to rise to the position shown in Figure 3. The buoyancy of the float 111 causes the washer 113 to be lifted off its seat, and oil is thus allowed to flow in volume through line 21 to the crankcase 12. When the crankcase becomes approximately one-half to three-quarters full, the refill valve 52 is closed tight. Since the level in the crankcase and float chamber 23 is below normal the float 83 drops down to the position shown in dot-dash lines in Figure 2, allowing the needle valve 71 to open and admit oil in relatively small volume until the level is brought to the normal operating height. As the oil in the float chamber 23 reaches normal level, the float 83 causes the needle valve 71 to close, thereby preventing admission of any more oil. From then on, the float-controlled needle valve automatically maintains the oil at normal level at all times, replenishing that which is used up by the engine during its operation.

While I have shown and described above in considerable detail what I consider to be the preferred form of my invention, it is to be understood that such details are not restrictive but that various changes may be made in the shape and arrangement of the several parts without departing from the broad scope of the invention as defined in the appended claims.

I claim:

1. A lubricating oil supply system for use with an oil storage tank and an engine having an oil sump, said system comprising a housing having a float chamber communicating with said sump below the oil level thereof and disposed so that the oil in the chamber is at the same level as in the sump, a valve compartment communicating with said chamber, a manually controlled refill valve disposed within said compartment and operable to close the same off from said chamber, an oil line connecting said storage tank with said valve compartment, a passage formed in said refill valve open at one end to said compartment and at the other end to said float chamber, a valve member arranged within said passage, and a float disposed within said chamber and engageable with said valve member to hold the same closed when the oil level in the chamber is at

normal height, said float permitting said valve member to open when the level in the chamber drops due to consumption of the oil in said sump by said engine, whereby oil from said storage tank is admitted to said float chamber and thence to said oil sump to restore the level in said sump and said float chamber to normal.

2. A lubricating oil supply system for use with an oil storage tank and an engine having an oil sump, said system comprising a housing having a float chamber communicating with said sump below the oil level thereof and disposed so that the oil in the chamber is at the same level as in the sump, a valve compartment communicating with said chamber, an oil line connecting said storage tank with said compartment, a manually controlled refill valve movable axially within said compartment between open and closed positions and operable to admit oil in relatively large volume to said chamber and sump to refill the latter rapidly after draining, a passage formed in said refill valve open at one end to said compartment and at the other end to said float chamber, a valve seat formed in said passage, a needle valve slidably disposed within said chamber and adapted to close on said seat, spring means yieldingly urging said needle valve away from said seat, and a float within said chamber engageable with said needle valve to close the same on said seat against the pressure of said spring means when the oil within the chamber is at normal level, said float permitting said needle valve to move away from said seat responsive to the urging of said spring means when the level within said chamber drops below normal to admit oil to the chamber and thence to said sump to replace oil used by said engine.

3. A lubricating oil supply system for use with an oil storage tank and an engine having an oil sump, said system comprising conduit means connecting said tank with said sump and including a refill valve operable to admit oil in relatively large volume from said tank to said sump to refill the latter rapidly after draining, a passage extending through said refill valve, and a second valve disposed within said passage and operable when said refill valve is closed to admit oil automatically at a rate to replenish the oil in said sump as used up by said engine.

4. A lubricating oil supply system for use with an oil storage tank and an engine having an oil sump, said system comprising a float chamber, a line connecting said chamber with said tank, an outlet opening in the bottom of said chamber, a second line connecting said outlet opening with said sump, a float-controlled valve for admitting oil in relatively small volume from said first-named line to said chamber and thence to said sump to replace the oil used up by said engine, a member seating on said outlet opening and having a hole provided therein forming a restriction which is relatively ineffective on the volume of oil admitted by said valve but which prevents the surging of oil from said float chamber to said sump, and means for removing said member from its seat to permit oil to flow in large volume from said chamber to said sump.

5. A lubricating oil supply system for use with an oil storage tank and an engine having an oil sump, said system comprising a float chamber, a line connecting said chamber with said tank, an outlet opening in the bottom of said chamber, a second line connecting said outlet opening with said sump, a float disposed within said chamber, a valve controlled by said float for admitting oil

in relatively small volume from said first-named line to said chamber and thence to said sump to replace the oil used up by said engine, a washer seating on said outlet opening and having a central hole provided therein forming a restriction which is relatively ineffective on the volume of oil admitted by said valve, but which prevents the surging of oil from said float chamber to said sump, a second float in said chamber, a member on said second float extending through the hole in said washer and engageable therewith to lift the washer from its seat when said chamber becomes flooded to permit oil to flow in large volume from said chamber to said sump, and means permitting the free flow of oil from said chamber to said sump but preventing the surging of oil in the reverse direction.

6. A lubricating oil supply system for use with an oil storage tank and an engine having an oil sump, said system comprising a float chamber, a line connecting said chamber with said tank, an outlet opening in the bottom of said chamber, a second line connecting said outlet opening with said sump, a float disposed within said chamber, a valve controlled by said float for admitting oil in relatively small volume from said first-named line to said chamber and thence to said sump to replace the oil used up by said engine, a washer seating on said outlet opening and having a central hole provided therein forming a restriction which is relatively ineffective on the volume of oil admitted by said valve, but which prevents the surging of oil from said float chamber to said sump, a second float in said chamber, a vertically disposed indicator stick extending upwardly from said float, a transparent inspection window to permit said stick to be viewed from the outside to check the level of the oil in said chamber, said stick having a downward extension passing through the hole in said washer, means on said stick engageable with the bottom of said washer to lift the latter from its seat when said float chamber becomes flooded to permit oil to flow from the chamber to said sump in large volume, and a normally closed butterfly valve pivoted to one side of its center in said second line, said butterfly valve being operative, when closed, to permit the relatively small volume of oil admitted by said needle valve to pass from said float chamber to said sump without restraint, but preventing the surging of oil from the sump back to the chamber, said butterfly valve being moved to fully open position by the pressure of oil flowing in large volume from said chamber to said sump.

7. A lubricating oil supply system for use with an elevated oil storage tank and an engine having a crankcase, said system comprising a housing adapted to be mounted on said crankcase and having a float chamber provided therein, a valve compartment opening into said chamber, a line connecting said tank with said compartment, an outlet opening in the bottom of said chamber, a second line connecting said outlet opening with said crankcase below the level of the oil contained therein, a normally closed, manually operable refill valve disposed within said compartment and adapted to admit oil in relatively large volume to said chamber and thence to said crankcase to refill the latter rapidly after draining, a passageway in said refill valve opening at one end into said compartment and at the other end into said chamber, a needle valve slidably disposed within said passageway and movable between open and closed positions, an annular

float within said chamber engageable with said needle valve when the level in the chamber is at normal height to hold said valve closed, said float permitting said needle valve to open and admit oil into said chamber in relatively small volume to replace the oil used up by said engine, a washer seating on said outlet opening and having a central hole provided therein forming a restriction which is relatively ineffective on the volume of oil admitted by said needle valve but which is operative to prevent surging of oil from said chamber to said crankcase, a second float disposed within said chamber, a rod on said second float extending down through the hole in said washer and engageable with the washer to lift the same from its seat when said chamber becomes flooded by said refill valve to permit oil to flow in large volume from said chamber to said crankcase, and means permitting the free flow of oil from said chamber to said crankcase but preventing the surging of oil in the reverse direction.
